United States Patent

Des. 238,290
Patented Dec. 30, 1975

238,290

GAME BOARD

Justin V. Dobbs, Rte. 5, Columbus, Ind. 46725

Filed Feb. 28, 1974, Ser. No. 446,617

Term of patent 7 years

Int. Cl. D21—01

U.S. Cl. D34—5 SS

Fig. 1

Fig. 2

FIG. 1 is a perspective view of a game board showing my new design; and

FIG. 2 is a top plan view thereof.

The side and end opposite the side and end shown in FIG. 1 are identical to side and end shown in FIG. 1.

I claim:

The ornamental design for a game board, as shown and described.
